UNITED STATES PATENT OFFICE.

WALTER S. ENGEL AND CHARLES L. ENGEL, OF KANSAS CITY, MISSOURI.

BINDING FOR BOOKS.

Application filed August 19, 1921. Serial No. 493,574.

To all whom it may concern:

Be it known that we, WALTER S. ENGEL and CHARLES L. ENGEL, citizens of the United States, residing at Kansas City, in the county of Jackson and State of Missouri, have invented a certain new and useful Improvement in Bindings for Books, of which the following is a specification.

Our invention relates to improvements in 10 bindings for books. It relates particularly to bindings for leaves permanently sewed together.

One of the objects of our invention is to provide a cover for a book which is strong, durable, cheap to make, which will withstand hard usage, and which is substantially fire proof.

A further object of our invention is the provision of a novel back member for a 20 book which is made of one piece of material and which is provided with integral hubs on its outer side.

A further object of our invention is to provide novel and efficient means for attaching the cover members to the back and to the bound leaves.

Still another object of our invention is to provide in the back substantially fire proof means for protecting the leaves.

Our invention provides further a novel one piece cover member.

The novel features of our invention are hereinafter fully described and claimed.

In the accompanying drawing which illustrates the preferred embodiment of our invention,

Fig. 1 is a plan view of our improved book, partly broken away, with the cover members in the open position.

Fig. 2 is a cross section on the line 2—2 of Fig. 1.

Fig. 3 is a perspective view of the outer back member.

Fig. 4 is a perspective view of the inner back member and the plates hinged thereto.

Fig. 5 is a perspective view of a portion of the bound leaves and the tapes secured thereto.

Fig. 6 is a perspective view of one of the cover members.

Similar reference characters designate similar parts in the different views.

The back of the book comprises an outer back member 1, preferably a single piece of material, such as vulcanized fibre, and having integral hubs 2 on its outer side. The

inner side of the member 1 is transversely curved, and the ends of the members are respectively provided with integral inwardly extending flanges 3.

Mounted on the inner side of the member 1 and secured thereto in any suitable manner, as by screws 4 is an inner back member 5, preferably of substantially non-inflammable material, such as sheet metal. The longitudinal edges of the member 5 are formed into longitudinal barrels 6 the ends of which are covered by the flanges 3. Mounted in the barrels 6 are pintles 7 to which are hinged respectively two metal plates 8, as best shown in Fig. 4. The flanges 3 prevent the removal of the pintles 7.

9 designates two cover members, preferably each comprising a single piece of vulcanized fibre. Each member 9 is provided on its inner side with a rectangular recess which extends to the inner edge of the cover member and which is provided with a relatively shallow portion 10 and a deeper portion 11.

The hinge plates 8 are respectively fitted in the deeper portions 11 and may be secured to the covers 9 by screws 12.

13 designates leaves permanently bound together at their inner edges by sewing, or stitching. Secured to the bound edges of the leaves 13 are tapes 14, which overlap at their projecting ends the plates 8, to which the tapes are secured by securing members 15 comprising thin plates which are respectively fitted and glued in the marginal portions 10 of the recesses in the cover members 9.

By having the plate 5 and hinge plates 8 of non-inflammable material, such as sheet steel, a substantially fire proof structure is afforded for the bound inner edges of the leaves and for the connection between the cover members and the back.

Our improved book binding is particularly adapted for large record books, which are heavy and are subjected to severe usage. Such books are usually disposed singularly flatwise between closely adjacent metal shelves, so that the backs of the books are the most exposed to damage from fire. By providing the protective covering in the back, the leaves of the book are not liable to be easily damaged by fires which may break out in a vault or other place where the books are stored.

By providing backs and cover members of vulcanized fibre, each member comprising a single integral piece, a very durable binding is afforded and which does not require canvas or other covering.

We do not limit our invention to the structure shown and described, as many modifications, within the scope of the appended claims, may be made without departing from the spirit of our invention.

What we claim is:

1. In a device of the kind described, the combination with a back and two cover members, of two plates hinged to opposite longitudinal edges of said back and respectively fastened to one side of said cover members, leaves bound together at their inner edges, one or more transverse tapes attached to the bound inner edges of the leaves and at opposite ends respectively overlapping said hinged plates, and two securing members respectively attached to said cover members and extending over and securing said tapes to said hinged plates respectively, substantially as set forth.

2. In a device of the kind described, the combination with a back, of two cover members, each having on one side a recess, two plates hinged respectively to opposite longitudinal edges of the back and respectively fitted and secured in said recesses, leaves bound together at their inner edges, one or more transverse tapes attached to the bound inner edges of the leaves and at opposite ends respectively overlapping said hinged plates, and two securing members respectively attached to said cover members and extending over and securing said tapes to said hinged plates respectively, substantially as set forth.

3. In a device of the kind described, the combination with a back, of two cover members, each having at one side a marginal portion of less depth than the remaining portion, two plates hinged respectively to opposite longitudinal edges of the back and respectively fitted in the deeper portions of said recesses, leaves bound together at their inner edges, one or more transverse tapes attached to the bound inner edges of said leaves and at opposite ends overlapping said hinged plates, and two securing members respectively fitted in and secured to said marginal portions and extending over and securing said tapes to said hinged plates respectively, substantially as set forth.

4. In a device of the kind described, the combination with a back comprising an outer and an inner member fastened together, of two cover members, two plates respectively hinged to opposite longitudinal edges of said inner member and respectively fastened to one side of said cover members, leaves

bound together at their inner edges, one or more transverse tapes attached to the bound inner edges of said leaves and at opposite ends respectively overlapping said hinged plates, and means covering said tapes and attached to said cover members and attaching said tapes to said hinged plate, substantially as set forth.

5. In a device of the kind described, a back of a book comprising an inner member and an outer member attached together, the inner member having longitudinal barrels formed respectively in its longitudinal edges, the outer member having inwardly extending flanges at opposite ends extending over the adjacent ends of the adjacent barrels, pintles mounted respectively in said barrels, said flanges extending across the opposite ends respectively of said pintles in position to obstruct the withdrawal of the latter from said barrels, and two cover member supporting plates respectively hinged to said pintles, substantially as set forth.

6. In a device of the kind described, the back of a book comprising an outer member having at its ends inwardly extending flanges and an inner metal plate attached to the outer member and having barrels at its longitudinal edges over which said flanges extend, pintles in said barrels respectively, two metal plates respectively hinged to said pintles, two cover members to which said hinged plates are respectively secured, leaves bound permanently together at their inner edges, and means for attaching said leaves to said cover members, substantially as set forth.

7. In a device of the kind described, the back of a book comprising an outer member having inwardly extending flanges at its ends and an inner metal plate attached to the inner side of said outer member and having at its longitudinal edges barrels over which said flanges extend, pintles in said barrels respectively, two cover members each having on its inner side a recess which extends to the inner edge of the member, two metal plates hinged respectively to said pintles and respectively secured to said cover members in said recesses, leaves bound permanently together at their inner edges, one or more tapes secured to the inner edges of said leaves and overlapping said metal plates, and securing members attached respectively to the cover members and overlapping and securing said tapes to said hinged plates substantially as set forth.

In testimony whereof we have signed our names to this specification.

WALTER S. ENGEL.
CHARLES L. ENGEL.
